(57) **CLAIM**

The ornamental design for an automotive wheel, as shown and described.

DESCRIPTION

FIG. 1 is a perspective view of an automotive wheel;

FIG. 2 is a front elevation view thereof;

FIG. 3 is a right side elevation view thereof;

FIG. 4 is a back elevation view thereof;

FIG. 5 is a top plan view thereof;

FIG. 6 is a vertical sectional view taken along the center of the front view;

FIG. 7 is a sectional view taken along line 7-7 of FIG. 2; and, FIG. 8 is a sectional view taken along line 8-8 of FIG. 5. The left side elevation view and the bottom plan view are mirror images of the right side elevation view of FIG. 3 and the top plan view of FIG. 5, respectively, and thus are omitted.

The broken lines shown are included for the purpose of illustrating portions of the article which form no part of the claimed design.

The one-dot chain lines shown each represents the borderline between the claimed portion and the non-claimed portion of the automotive wheel, and forms no part of the claimed design.
